UNITED STATES PATENT OFFICE

WILLIAM F. HELMOND, OF WEST HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed July 31, 1929. Serial No. 382,327.

This invention relates to the paper-carriages of typewriting machines, such as the Underwood, and especially to improvements in means whereby the work-sheet is guided around the platen.

One of the objects of the invention is to facilitate the introduction and adjustment of the work-sheet or pack of work-sheets, and to improve the feeding of the sheets, and to decrease the noise of operation, especially of the sheet-metal frame in which the platen is mounted.

It is usual in the Underwood machine to employ at the back of the platen a paper-shelf which is fastened upon the platen-frame and extends downwardly and forwardly to the platen, and around under the same and up in front. This device, if made so strong that it will control a pack of work-sheets, is so stiff that it is sometimes difficult to manipulate the sheets in the machine, and it does not afford sufficient clearance for the sheets in all cases. A feature of the invention is to cut off the paper-shelf at a point that is about level with the platen-axle, and to provide an independent downward continuation of said paper-shelf in the form of a hinged paper-guiding apron, which is hinged just below the bottom edge of the paper-shelf and continues downwardly and forwardly and curves around the bottom of the platen and up in front thereof. This paper-guiding apron has a spring which tends to lower it from the platen. The apron is held up, however, by means of rubber pads, which are provided upon the shafts which carry the usual releasable rear and front rolls. The paper-apron is held up in correct position by these pads; and they also aid in deadening the vibration and noise. When the feed-rolls are cast off from the platen, the pads drop therewith, together with the paper-apron resting thereon, which at this time curves about concentrically with the platen and leaves ample space for the introduction of a thick pack of sheets, and is also convenient for the introduction downwardly of sheets in front of the platen.

Said feed-rolls are cast off by means of a rock-shaft which extends along the platen and below the same, and is provided with

cams to control the feed-roll-arms. Provision is made whereby this cam-shaft can be readily trued up, so as to bring the rolls into correct positions for guiding the work-sheets, and also for sustaining the paper-apron in its correct elevated and dropped positions.

The vibration of the aforesaid paper-shelf is deadened by means of a pad which is compacted between the same and the platen-frame back.

Other features and advantages will herein-after appear.

In the accompanying drawings,

Figure 1 is a front perspective view, partly broken away, showing the platen-frame of an Underwood typewriting machine provided with the present improvements.

Figure 2 is a sectional side elevation, showing the parts in normal positions.

Figure 3 is similar to Figure 2, but shows a smaller platen, and shows the feed-rolls cast off therefrom.

Figure 4 is a sectional side elevation to illustrate the manner of bending one of the hangers that carry the roll-releasing cam-shaft.

Figure 5 is a perspective rear end view of the platen-frame and other parts.

Figure 6 is a detail of mounting of the pad-collars on the feed-roll shafts.

Type-bars 10 strike upon the front of a platen 11, having an axle 12 whereby it is journaled in the ends 13, 14 of a platen-frame, said ends being joined by a tie-bar 15, which is fastened by screws 16 to flanges 17 bent in from the platen-frame ends.

Upon the bottom of the platen run large rear rolls 18 and small front rolls 19, which may be dropped away from the platen to release the work-sheet; the usual release-key being shown at 20, pivoted at 21 to the platen-frame, and connected by a link 22 to a crank 23 provided upon a release-shaft 24.

At each end of the release-shaft are formed cutaways 25, 26 upon its opposite sides. These cutaways are occupied by the ends of arms 27 for the rear rolls, and arms 28 for the front rolls. Said arms form portions of bell-cranks that are loosely journaled upon

a tie-rod 29 that connects the ends of the platen-frame.

The rear rolls are loosely pivoted upon a shaft 30, carried by arms 31 extending rearwardly from the tie-rod 29 and joined to the arms 27 to form bell-cranks. The front rolls are supported upon a shaft 32 carried by bell-crank arms 33, joined to or integral with the arms 28 to form another set of bell-cranks. Springs 34, 35 of usual construction press the arms 31, 33 toward the platen, to give the rolls 18, 19 the desired work-feeding pressure upon the platen.

The work-sheet may be introduced at the rear upon an upwardly-and-rearwardly inclined paper-shelf 36, and guided downwardly and forwardly between the platen and the feed-rolls, and thence up to the front of the platen. The paper-shelf 36 is fastened by means of screws 37 upon the tie-bar 15, and has a rigid relation to the platen-frame, but terminates at a point that is about level with the platen-axle, instead of continuing downwardly and forwardly under the platen, as heretofore in Underwood typewriting machines.

A paper-guiding apron for the under side of the platen is made separately from the paper-shelf, and is hinged at its upper end at 38 to the platen-frame by means of a pintle 37^a mounted in the platen-frame-ends. From this hinge the paper-apron extends downwardly and forwardly to the rear rolls 18 and past the same, and then forwardly under the platen at 39 and upwardly past the front rolls, terminating in an upwardly-and-forwardly projecting lip 40. The hinged apron is provided with cutaways 41 for the rolls, of which a number are provided upon each roll-shaft, Figure 1, said cutaways extending through the front end of the hinged paper-apron.

Weak leaf-springs 42 extend down from the ends of the paper-shelf 36, and are caught in eyes 43 provided upon the rear of the paper-apron, and tend to swing said apron downwardly and constantly press the apron down against annular soft rubber or felt pads 44 provided upon collars 45 that are mounted upon the ends of the roll-shafts 30, 32. These rubber pads have a dampening effect upon the vibrations of the paper-apron, and reduce its noise.

One of the aims of the invention is to increase the clearance for the introduction of the work-sheets under the platen, and it is for this reason that the paper-apron is made separately from the fixed paper-shelf, and is hinged at such a point that its forward edge 40 will swing down far enough to form an ample throat for the introduction of paper either forwardly or backwardly under the platen, as at Figure 3. The curvature of the paper-apron and the position of its hinge 38 are preferably such that in its dropped po-

sition, Figure 3, it is about concentric with the platen, leaving a wide-open throat or chute for the paper around the bottom of the platen. This is a convenience, especially in inserting sheets downwardly in front of the platen, as at Figure 3, the sheet being introduced between the platen and the usual type-guide 47.

The soft rubber pads 44 (which are in the form of rings confined in peripheral grooves of metal collars 45, held by headed screws 49 upon the loose ends 50 of the roll-shafts, Figure 6) not only dampen the vibrations of the paper-apron, but also position the same properly near to the platen after the work-sheet has been introduced, the sheet being pressed against the platen preferably by the rolls and not by the paper-apron.

As seen at Figure 3, in order to provide for a spacious work-chute under the platen, the latter may be reduced in diameter from the standard Underwood measurement, and the platen-axle may be set forwardly a little, so as to bring the front of the reduced platen to proper printing position with reference to the types.

At Figure 2, the positions of the parts are shown for feeding the work-sheet around the platen. The release-key 20 and shaft 24 are in normal positions, and it will be seen that the roll-releasing arms 27, 28 are contiguous to the flattened portions of said shaft 24. If it should happen during manufacture, or during shipment, or in using the machine, that said shaft should get a little out of true, it would tend to swing either the front or rear roll away from the platen. This fault would also be apparent when the rolls are released, as at Figure 3, at which time either the left-hand or right-hand portion of the hinged paper-apron would be raised by one roll off from the other roll, according to the faulty positioning of the release-shaft 24. To meet this difficulty, the hangers 51, which support the release-shaft 24, and which are fastened by pins 52 to the ends of the tie-rod 29, are formed with cuts 53, which leave a thin neck 54 to join the ends of each hanger, these necks being sufficiently thin to permit bending of either hanger either forwardly or backwardly by means of pliers, as indicated by dotted lines at Figure 4. By this adjustment, the position of the front and back rolls at either end of the platen may be readily corrected.

The release-shaft 24 passes through an eye 55 in a bracket 56, the latter being mounted on the middle of tie-rod 29, and at its lower end carrying a shift-roller 57. The release-shaft 24 may be reduced at 58, where it passes through said eye, so as to afford clearance to permit the bending of either hanger 51.

At its lower end, the paper-shelf 36 may be provided with a longitudinal rib 59 bordered by a tubular bead 60 at its lower edge, which is adjacent the hinge 38 of the paper-

apron, said rib being in the same inclined plane as the paper-apron, and the work-sheet being directed properly to the bight of the platen and the rear feed-roll.

5 For further dampening or reducing the vibration of the platen-frame, a thick pad of felt 61 is held against the back of the paper-shelf, being inserted between the same and the tie-bar 15, and being held thereto by the screws 37. This pad extends down to the bottom of the paper-shelf, and its lower end is held thereagainst by screws 62 which fasten the springs 42.

15 Variations may be resorted to within the scope of the invention, and portions of the improvements may be used without others.

Having thus described my invention, I claim:

20 1. In a typewriting machine having a revolute platen and a carriage, including a platen-frame, the combination of a paper-shelf in rear of the platen and inclined downwardly and forwardly and terminating with its lower edge about level with the platen-axle, a paper-guiding apron hinged in juxtaposition to said lower edge, and inclined downwardly and forwardly therefrom and curving around the bottom of the platen and up in front thereof, a spring tending to swing said paper-apron down from the platen, soft pads, down against which the paper-apron is pressed by the spring, a set of feed-rolls running upon the under side of the platen, spring-supported arms carrying said feed-rolls, said pads being mounted upon said arms, a cam-shaft extending along the platen beneath the same, supports for the ends of said cam-shafts, and a key for rocking said cam-shaft to swing the roll-carrying arms down from the platen, said cam-shaft supports being independently adjustable forwardly or backwardly.

25 2. In a typewriting machine having a revolute platen and a carriage, including a platen-frame, the combination of a paper-shelf in rear of the platen and inclined downwardly and forwardly and terminating with its lower edge about level with the platen-axle, a paper-guiding apron hinged in juxtaposition to said lower edge, and inclined downwardly and forwardly therefrom, and curving around the bottom of the platen and up in front thereof, a spring tending to swing said paper-apron down from the platen, soft pads, down against which the paper-apron is pressed by the spring, a set of feed-rolls running upon the under side of the platen, spring-supported arms carrying said feed-rolls, said pads being mounted upon said arms, a cam-shaft extending along the platen beneath the same, and a key for rocking said cam-shaft to swing the roll-carrying arms down from the platen, said platen-frame having brackets in which the ends of said cam-shaft are mounted, said brackets having thin necks readily bendable.

forwardly or backwardly to true the cam-shaft.

3. In a typewriting machine having a revolute platen and a carriage, including a platen-frame, the combination of a paper-shelf 70 in rear of the platen and inclined downwardly and forwardly and terminating with its lower edge about level with the platen-axle, a paper-guiding apron hinged in juxtaposition to said lower edge, and inclined downwardly and forwardly therefrom, and curving around the bottom of the platen and up in front thereof, a spring tending to swing said paper-apron down from the platen, soft 80 pads down against which the paper-apron is pressed by the spring, a set of feed-rolls running upon the under side of the platen, and spring-supported arms carrying said feed-rolls, said soft rubber pads in the form of rings, said rolls mounted upon shafts, each 85 shaft having at each end a collar having a peripheral groove to carry said pad-rings.

4. In a typewriting machine having a revolute platen and a carriage, including a platen-frame, the combination of a paper-shelf 90 in rear of the platen and inclined downwardly and forwardly and terminating with its lower edge about level with the platen-axle, a paper-guiding apron hinged in juxtaposition to said lower edge, and inclined downwardly and forwardly therefrom, and curving around the bottom of the platen and up in front thereof, a spring tending to swing said paper-apron down from the platen, soft 95 pads down against which the paper apron is pressed by the spring, a set of feed-rolls running upon the under side of the platen, spring-supported arms carrying said feed-rolls, said pads being mounted upon said arms, a cam-shaft extending along the platen beneath the 100 same, a key for rocking said cam-shaft to swing the roll-carrying arms down from the platen, said platen-frame having a tie-rod, hangers fixed upon said tie-rod and formed with bendable necks, and a release shaft 110 mounted in said hangers and having an operating key.

WILLIAM F. HELMOND.
